UNITED STATES PATENT OFFICE.

FRANCIS A. WILLIAMS, OF BROOKLYN, ASSIGNOR TO RUTZLER & BLAKE, OF NEW YORK, N. Y.

DESIGN FOR A FURNACE-FRONT.

SPECIFICATION forming part of Design No. 18,123, dated February 29, 1888.

Application filed December 24, 1887. Serial No. 258,031. Term of patent 14 years.

To all whom it may concern:

Be it known that I, FRANCIS A. WILLIAMS, of the city of Brooklyn, in the county of Kings and State of New York, have invented and produced a new and original Design for a Furnace-Front, of which the following is a specification, reference being had to the accompanying drawings, forming parts thereof.

Figure 1 represents a face view of my newly-
10 designed furnace-front. Fig. 2 represents a horizontal section in the line $x-x$ of Fig. 1, showing one-half the width of the furnace-front. Fig. 3 represents a horizontal section of half the furnace-front in the line $y-y$, Fig. 1.
15 Similar letters of reference designate corresponding parts in the several figures.

The body-plate A of the furnace-front is flat. Its contour is square, except that the central portion of the top is arched at a , and
20 its corners are projected horizontally from the sides in horizontal lines b and curves c , and there are horizontal projections composed each of straight lines d d' and curves e . The said plate is surrounded by a raised molding consisting, as shown in Figs. 2 and 3, of a fillet, f , and cavetto g . It has on its upper part a central flat raised panel, h , of circular outline, and on each side of said panel h a flat raised panel, i , of segmental form, conforming to the
25 arch a , as shown in Fig. 1; and it has on the lower part, at each side, three panels, j k l , one above another, the central one, j , having a circular outline and the others having an oblong square outline, except that their bottoms
30 are curved to conform to j and their upper corners are composed of hollow curves. The transverse sectional profile of the edges of all the panels consists of a cavetto, l , as shown in Fig. 2, wherein the panels h and i are represented.

The upper doors, B, have their outline of square form, with their outer corners rounded. The lower doors, C and D, have their upper parts arched and their sides and bottoms square, with rounded outer corners.

The doors project from the body-plate A, and all have similar marginal moldings, the said moldings each consisting, as shown in Fig. 3, of a fillet, m , having cavettos n in its sides, and outside of this an ovolo, o . The doors 50 have also in their panels r , within the outer molding, a bead, P , the outline of which is in the form of an oblong square having its lines prolonged at the corners and formed into squares q .

55

What I claim is—

1. In a design for a furnace-front, the plate A, having upright sides and an arched top, with its upper and lower corners projecting from the sides in horizontal lines b and curves 60 c , and with side projections formed with straight lines d d' and curves e e' , and having on its face the raised segmental panels i i , circular panels j , and the panels k l above and below said circular panels, arranged substantially as shown and described.

65

2. In a design for a furnace-front, a door of rectangular form with rounded outer corners, and with a molding, m n n o , around its edge, and having on its surface a bead, p , the outline of which is an oblong square with its corners prolonged and formed into projecting squares q , substantially as herein shown and described.

70

3. The design for a furnace-front, consisting of the plate A, having upright sides and arched top, with corners projecting in horizontal and curved lines b c , and with side projections formed of straight lines d d' , and curves e e' , and having on its face the panels i j k l , 75 and the doors B, of rectangular form, with rounded corners and moldings m n n o , and beads p , of oblong form, with squares q q at the corners, substantially as herein shown and described.
